Primary Examiner — Khawaja Anwar*Assistant Examiner* — Mojtaba Tehrani(74) *Attorney, Agent, or Firm* — Fox Rothschild LLP(57) **CLAIM**

The ornamental design for a firearm safety lever, as shown and described.

DESCRIPTION

FIG. 1. is an isometric view of a first embodiment of a firearm safety lever showing my new design;

FIG. 2. is a front view;

FIG. 3. is a rear view thereof;

FIG. 4. is a right side view thereof;

FIG. 5. is a left side view thereof;

FIG. 6. is a top view thereof;

FIG. 7. is a bottom view thereof;

FIG. 8. is an isometric view of a second embodiment of a firearm safety lever showing my new design;

FIG. 9. is a front view thereof;

FIG. 10. is a rear view thereof;

FIG. 11. is a right side view thereof;

FIG. 12. is a left side view thereof;

FIG. 13. is a top view thereof; and,

FIG. 14. is a bottom view thereof.

The dot-dash broken lines in the drawings depict boundaries of the claimed design. The evenly broken lines in the drawings depict unclaimed portions of the firearm safety lever. The broken lines form no part of the claimed design.

1 Claim, 4 Drawing Sheets(56)
